HANDLE

Larkin R. Shaffer, Garland, Utah

Application May 7, 1940, Serial No. 333,818

3 Claims. (Cl. 294—33)

The present invention relates to new and useful improvements in handles and has for its primary object to provide, in a manner as hereinafter set forth, novel means whereby an ordinary tin can or similar container may be conveniently used as a cup or dipper.

Another very important object of the invention is to provide a handle of the character described which is adapted to be expeditiously and firmly attached to different sizes of cans or other containers.

Still another very important object of the invention is to provide handles of the cup and dipper types for attachment to a container, said handles comprising a novel construction and arrangement whereby they may be conveniently secured together for shipment.

Other objects of the invention are to provide a handle of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a dipper type handle constructed in accordance with the present invention, showing the device mounted on a can.

Figure 2 is a top plan view thereof.

Figure 3 is a cross sectional view, taken substantially on the line 3—3 of Figure 1.

Figure 4 is a cross sectional view, taken substantially on the line 4—4 of Figure 1.

Figure 5 is a view in side elevation of a cup type handle embodying the present invention, showing the device mounted on a can.

Figure 6 is a view in rear elevation thereof.

Figure 7 is a top plan view.

Figure 8 is a fragmentary view in vertical section, taken substantially on the line 8—8 of Figure 6.

Figure 9 is a top plan view, showing the dipper and cup type handles secured together, as for shipment.

Figure 10 is a view in side elevation of the arrangement shown in Figure 9.

Referring now to the drawings in detail, and to Figs. 1 to 4, inclusive, thereof in particular, it will be seen that the reference numeral 1

5 designates a handle of suitable metal, said handle being substantially C-shaped in cross section and further being open at both ends. At one end, the handle 1 is provided with an integral hook 2 constituting a bottle opener as well as providing means for hanging the device on a nail or other support.

The handle 1 is mounted for sliding adjustment on a resilient U-member 3 the legs 4 of which project from the forward end of said handle and terminate in oppositely extending arms 5. The arms 5 terminate, at their free ends, in hooks 6 and 7.

10 The upper hook 6 is engageable over the top of a conventional tin can or other container 8. The lower hook 7 is engageable selectively in openings 9 which are provided therefor in a metallic bar 10 having a substantially U-shaped, lateral foot 11 on its lower end engageable beneath the bottom of the can or other container 8.

15 A stop 12 is struck inwardly from the outer end portion of the handle 1 for preventing separation of said handle and the member 3. An opening 13 is formed in the outer end portion of the handle 1. The reference numeral 14 designates a comparatively long opening or slot in the inner end portion of the handle 1. The adjacent walls of the openings 13 and 14 are pressed outwardly in a manner to provide what 20 may be considered pockets or recesses 15 (see Fig. 4). The purpose of the openings 13 and 14 and the pockets 15 will be presently set forth.

25 It is thought that the manner of using the device will be readily apparent from a consideration of the foregoing. Briefly, the hook 7 is engaged in the correct hole 9 in the bar 10, the foot 11 is engaged beneath the bottom of the can 8 and the hook 6 is engaged over the top of said can. The handle 1 is then moved forwardly on the U member 3 in a manner to draw the legs thereof together, thus firmly clamping the can 8 between the hook 6 and the foot 11. The device may be conveniently adjusted to accommodate different sizes of cans by engaging the hook 7 in the desired opening 9 in the bar 10. Of course, to remove the device from the can it is only necessary to retract the handle 1, thus permitting the legs 4 of the U-member 3 to open or be opened. The upper end of the bar 10 has formed therein a notch or recess 16 which accommodates the upper hook 6 when the device is attached to a small can. Also, the hook 7 is engageable directly beneath the usual bead on the bottom of the can when said can

is so small that the adjustable extension bar 10 is not required.

Referring now to Figs. 5, 6, 7 and 8 of the drawings, it will be seen that the reference numeral 17 designates a resilient, substantially U-shaped member constituting a cup-type handle adapted to be removably mounted on the can 8. On the upper end of the handle member 17 is a depending, substantially U-shaped loop 18 which terminates, at one end, in a hook 19 engageable over the top of the can 8. On the lower end of the member 17 is a depending hook 20 which is engageable beneath the bead on the lower end of the can 8.

In the drawings, the member 17 is shown mounted on a comparatively small can. When the device is to be attached to a larger can, the adjustable extension bar 10 is used. When the bar 10 is used the hook 20 is engaged in one of the openings 9 thereof and the foot 11 is engaged beneath the bottom of the can.

When the bar 10 is not in use with the member 17, said member 17 constitutes means for holding said bar where it will always be conveniently available for use when needed. This is shown to advantage in Figs. 5 and 8 of the drawings. The hook 19 is engaged in the notch 16 in the upper end of the bar 10 and the resilient loop 18 is engaged with the upper portion of said bar. Then, the lower end of the bar 10 is secured to the can by the hook 20 and the shank 21 of said hook.

It may be well to here state that a bar 10 is to be provided with each of the two forms of the device. Referring now to Figs. 9 and 10 of the drawings, it will be seen that the two forms of the invention are adapted to be conveniently secured together for shipment. When this is done, the bar 10 on the member 3 is reversed so that the foot 11 thereon projects rearwardly instead of forwardly. The bar 10 of the cup handle is reversed on the member 17 and the loop 18 is inserted through the substantially U-shaped foot 11 thereof. The hook 20 is engaged in the notch 16 and the shank 21 is engaged with the adjacent end portion of the bar 10. The hook 20 is now inserted in the opening 13 and engaged in the pocket or recess 15 thereof and the hook 19 is inserted through the opening 14 and engaged in the recess or pocket 15

of said opening 14. It will thus be seen that the dipper type handle shown in Figs. 1 to 4, inclusive, of the drawings and the cup type handle, illustrated in Figs. 5 to 8, inclusive, of said drawings are firmly but detachably secured together.

It is believed that the many advantages of a handle constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. In a handle attachment for a receptacle, a handle, a bar having a plurality of openings therein, an element on said bar engageable beneath a receptacle, a hook on the handle engageable selectively in the openings for adjustably connecting said handle to said bar, and a second hook on the handle engageable with the top of the receptacle.

2. A handle for attachment to a receptacle, comprising a substantially U-shaped resilient member, arms projecting in opposite directions from the free ends of the legs of said member, a bar having a series of openings therein, a foot on one end of said bar engageable beneath the bottom of the receptacle, a hook on one of the arms engageable selectively in the openings for adjustably mounting the bar on the member, a hook on the other arm engageable with the top of the receptacle, and a handle slidable on the member for closing the legs thereof for clamping the receptacle between the foot and the second named hook.

3. A handle for attachment to a receptacle, comprising a substantially U-shaped resilient member, a hook on one end of said member engageable over the top of the receptacle, a bar having a series of openings therein, a foot on one end of said bar engageable beneath the bottom of the receptacle, and a hook on the other end of the member engageable selectively in the openings for adjustably connecting said member to said bar.

LARKIN R. SHAFFER.
